Primary Examiner — Paula Allen Greene(57) **CLAIM**

The ornamental design for an earphone, as shown and described.

DESCRIPTION

FIG. 1 is a first perspective view of an earphone showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the earphone in which the design is embodied that form no part of the claimed design.

The earphone cord that is drawn broken away in FIGS. 1-6 is shown with a symbolic break in its length. The appearance of any portion of the article between the broken away portions form no part of the claimed design.
